UNITED STATES PATENT OFFICE.

THOMAS HAGERTY, OF RICHMOND, VIRGINIA.

IMPROVEMENT IN ICE-HAMMERS, PICKS, AND LEMON-SQUEEZERS COMBINED.

Specification forming part of Letters Patent No. **155,579**, dated October 6, 1874; application filed July 16, 1874.

To all whom it may concern:

Be it known that I, THOMAS HAGERTY, of Richmond, in the county of Henrico and State of Virginia, have invented a Combined Ice-Hammer, Pick, and Lemon-Squeezer; and I do hereby declare the following to be a full, clear, and exact description of the same, reference being had to the accompanying drawings, forming part of this specification, in which—

Figure 1 is a side elevation. Fig. 2 is a section, in line *x x* of Fig. 1; and Fig. 3 is an edge view of the instrument open.

Similar letters of reference in the accompanying drawings indicate the same parts.

The object of this invention is to combine in one simple and convenient instrument, an ice-hammer, an ice-pick, and a lemon-squeezer; and to this end, the invention consists in the improved instrument constructed and operating as hereinafter described.

In the drawings, *A A'* are the handles, one being slotted laterally to accommodate the other, and the two being pivoted together at *p*; and, if preferred, recessed and corrugated at *n*, to form a nut-cracker. The front end of one of the handles is expanded into a cup, *C*, perforated to allow the lemon-juice to escape. The front end of the other handle is also expanded into a squeezer, *S*, which fits into the cup *C*, and serves to express the juice from

the lemon placed in the cup. The hammer-head *H* is attached to one edge, and the ice-pick *I* to the other edge, of the cup, as represented. The inside of the cup and the surface of the squeezer may be tinned or enamelled in any suitable manner, to prevent them from rusting.

Instead of a pick, a blade may be substituted, for the purpose of cutting the ice, and the end of the handle may be made sharp, to serve as a pick, or a pick may be attached to the front edge of the cup, opposite to the handles. The instrument should be made of malleable or wrought iron, to insure sufficient strength.

Having thus described my invention, what I claim is—

1. In a lemon-squeezer, the combination of the cup *C* and squeezer *S*, with the crossed and pivoted handles *A A'*, one passing through and working in a slot in the other, substantially as described.

2. The lemon-squeezer, constructed substantially as described, and provided with an ice-hammer and an ice-pick, arranged with relation to the head or compressing-plates thereof, substantially as described.

THOMAS HAGERTY.
